UNITED STATES PATENT OFFICE

SUMNER L. MORSE, OF ATHOL, MASSACHUSETTS.

VENTILATOR.

No. 802,013.

Specification of Letters Patent.

Patented Oct. 17, 1905.

Application filed January 31, 1905. Serial No. 243,520.

To all whom it may concern:

Be it known that I, SUMNER L. MORSE, a citizen of the United States, residing at Athol, in the county of Worcester and State 5 of Massachusetts, have invented a new and useful Ventilator, of which the following is a specification.

This invention relates to ventilators, and is designed to provide an improved device of 10 this character which is entirely complete in itself and capable of being placed beneath and also above a partially-open window-sash, so as to control the passage of air through the opening at the bottom or the 15 top of the sash and also to provide for deflecting the incoming air upwardly and over the head of a person situated adjacent the window, thereby to avoid a direct draft.

Another object of the invention is to provide 20 for the convenient adjustment of the device to fit windows of different widths without impairing the controlling of the air-current.

With these and other objects in view the 25 present invention consists in the combination and arrangement of parts, as will be hereinafter more fully described, shown in the accompanying drawings, and particularly pointed out in the appended claims, it 30 being understood that changes in the form, proportion, size, and minor details may be made within the scope of the claims without departing from the spirit or sacrificing any of the advantages of the invention.

35 In the accompanying drawings, Figure 1 is a front elevation of the bottom portion of a window having the ventilator of the present invention fitted beneath the lower sash. Fig. 2 is an enlarged longitudinal sectional 40 view on the line 2 2 of Fig. 1. Fig. 3 is a cross-sectional view on the line 3 3 of Fig. 2. Fig. 4 is a detail perspective view looking at the inner sides of the inner ends of the 45 slideable members of the device. Fig. 5 is a front elevation of the body of the device with the slideable members removed.

Like characters of reference designate corresponding parts in each and every figure of the drawings.

50 The device of the present invention comprises a back or body 1 preferably in the nature of an oblong wooden plate or bar of suitable dimensions and of a length to fit within a comparatively narrow window. Sets of 55 perforations 2, 3, 4, and 5 are formed through the back or body 1 at suitable intervals, each

set preferably including four perforations arranged around a common center. Some of the sets of perforations, preferably the two middle sets, are each provided with an 60 adjustable closure or valve 6, preferably in the nature of a metallic disk let into a recess in the front of the body, so as not to project at said front and rotatable upon a central fastening 7, there being an annular series of 65 openings 8 in the plate for alternate registration and non-registration with the perforations in the body, thereby to close said perforations, as desired. Each cut-off or closure 6 is provided with a projection 9, constituting a handle or finger-piece for the rotatable adjustment of the cut-off.

Mounted upon the front of the body 1 are two slides, (designated 10 and 11, respectively,) the slide 11 being shorter than the 75 slide 10 and located at the right-hand end of the body 1. For slidably connecting the members 1 and 11 the front of the member 1 is provided adjacent its top with a longitudinal groove 12, which is laterally inclined or 80 undercut for the reception of a correspondingly-inclined projection or rib 13, carried in a groove 14 in the inner side of the member 11 and corresponding to the groove 12, there being a set-screw 15 piercing the top edge of 85 the member 11 and engaging the rib or tongue 13, so as to rigidly hold the latter in place. In the right-hand end of the groove 12 in the member 1 there is a rib or projection 16, held in place by a set-screw 17, said 90 groove 18 in the lower portion of its inner face for the reception of a correspondingly-inclined tongue or rib 19, carried by the lower portion of the inner face of the member 1 and extending throughout the entire length 100 thereof. By reason of the lateral inclinations of the engaged grooves and ribs the members 1 and 11 are held against lateral separation, while at the same time the member 11 is capable of being slid in an endwise direction 105 upon the member 1. In addition to the ribs and grooves the member 11 is also provided with two longitudinal series of perforations 20 for successive alinement with the perforations 5 of the member 1, and there is 110 a metallic closure-plate 21 hinged at its lower edge, as at 22, to the front of the slide

11 below the openings 20 and designed to be folded up across the openings 20 to close the same, the closure-plate being held in its closed position by means of a pivotal latch or 5 turn-button 23, mounted upon the upper portion of the front face of the slide and capable of being turned across the upper free edge of the closure-plate when folded over the openings 20. The other slidable member 10 10 is provided with a groove 24, corresponding to the groove 12 of the member 1, and has a short rib or tongue 25, held within the inner end of the groove 24 by means of a set-screw 26, the rib 25 of course working in the 15 groove 12 and capable of contacting with a short rib or tongue 27, held in the left-hand end of the groove 12 by means of a set-screw 28, thereby to prevent endwise separation of the members 1 and 10. In the 20 lower portion of the inner face of the member 10 there is a longitudinal groove 29, receiving the rib or tongue 19 of the member 1. Between the slidable members 10 and 11 there is a projection 30, carried by the front 25 of the member 1 in the inward paths of the members 10 and 11, the inner ends of said members being respectively provided with notches 31 and 32 to receive the projection 30 at the inner limits of the members 1 and 30 10, and thereby permit of the latter coming into intimate contact. The slidable member 10 is also provided with three sets of perforations (designated 33, 34, and 35) for successive alinement with the sets of perforations 35 2, 3, and 4 of the body 1, and these sets of perforations are controlled by means of a closure-plate 36, hinged to the front of the member 10 below its sets of perforations, so as to be folded up across the perforations, 40 there being a pivotal latch or turn-button 37 mounted upon the top of the member 10 to hold the closure 36 when folded upwardly.

To illustrate the application and operation of the present ventilator, there have 45 been shown in Fig. 1 of the drawings the lower portion 38 of an ordinary window-frame and the lower portion of a lower sash 39, the latter being slightly elevated to permit of the ventilator being inserted between the 50 sill 40 and the bottom of the sash, the latter of course resting upon the top of the body 1, so as to hold the ventilator down upon the sill, the slides 10 and 11 being extended to fit against the sides of the window-frame. As 55 illustrated in Fig. 1, the slides 10 and 11 are separated sufficiently to expose the set of perforations 4 in the body 1, and these perforations may be controlled by the cut-off 6, so as to open or close the perforations, as 60 may be desired. The perforations of the slide 10 are out of alinement with the adjacent perforations of the member 1, while certain of the perforations of the slide 11 are registered with the perforations 5 of the member 65 1, the closure 21 being open.

It will here be explained that the hinges of the closure members 21 and 36 are sufficiently stiff to support each of said closures in an inclined position, as indicated by dotted lines in Fig. 3, whereby each closure is 70 adapted to operate as a deflector to deflect the incoming current of air upwardly and above the head of a person situated adjacent the window, wherefore said person is not subjected to a direct draft.

From the foregoing description it will be understood that the device of the present invention is entirely complete in itself and capable of application to a window without altering or changing the latter in any manner 80 whatsoever and does not require any extraneous fastenings to support the device in its operative position. Moreover, by means of the slides 10 and 11 the device may be adjustably extended to fit windows of different 85 widths, and the various sets of perforations may be opened and closed at will, so as to regulate the amount of ventilation.

Having fully described the invention, what is claimed is—

1. A ventilator comprising a body having sets of perforations, a slidable member carried by the body and capable of projection beyond the body to extend the device and provided with perforations for registration 90 with the perforations of the body, and a cut-off for the perforations of the body which are exposed by the extension of the slidable member.

2. A ventilator comprising a body having sets of perforations, a slidable member carried by the body and capable of projection beyond the body to extend the device and provided with perforations for registration 100 with the perforations of the body, a cut-off 105 for the perforations of the slidable member, and another cut-off for the perforations of the body which are exposed by the extension of the slidable member.

3. A ventilator comprising a body having 110 perforations and slidable members carried by the body and capable of projection at opposite ends thereof to extend the device, said slidable members having perforations for alinement with the perforations of the body 115 in adjusted positions of the slidable members.

4. A ventilator comprising a body having perforations slidable members carried by the body and capable of projection at opposite 120 ends thereof to extend the device, each slidable member having perforations for registration with the perforations of the body in adjusted positions thereof, and a stop carried by the body for engagement by the respective slides to limit inward adjustments 125 thereof.

5. A ventilator comprising a body having perforations, a slide capable of projection beyond the body to extend the device, said 130

slide having perforations for registration with the perforations of the body in adjusted positions thereof, and a hinged closure for the perforations carried by the slide and capable of being set at different upward inclinations to form a deflector for incoming currents of air.

6. A ventilator comprising a body having sets of perforations, rotary cut-offs for the intermediate sets of perforations, each cut-off being let into the front face of the body, slideable members working endwise across the front face of the body and capable of projection at each end thereof to extend the body,

each slideable member having perforations 15 for successive alinement with the sets of perforations of the body, and hinged closures for the perforations of the slideable members, each closure capable of being set at different vertical inclinations to form a deflector. 20

In testimony that I claim the foregoing as my own I have hereto affixed my signature in the presence of two witnesses.
